United States Patent

Des. 240,829
Patented Aug. 3, 1976

240,829

AEROSOL CONTAINER FOR AIR FRESHENER

David A. Jones, Bellbrook, Ohio, and Raymond E. Benson, Riverside, and John R. Howard, West Chicago, Ill., assignors to The Drackett Company, Cincinnati, Ohio

Filed Apr. 21, 1975, Ser. No. 570,045

Term of patent 14 years

Int. Cl. D23—03

U.S. Cl. D23—150

FIG. 1 is a perspective view of an aerosol container for air freshener, showing our new design;

FIG. 2 is a side elevational view thereof;

FIG. 3 is a top plan view thereof; and

FIG. 4 is a bottom plan view thereof.

We claim:

The ornamental design for an aerosol container for air freshener, as shown and described.
